TOY TANK

Walter F. Springall, Houston, Tex.

Application December 9, 1954, Serial No. 33,461

Term of patent 7 years

(Cl. D34—15)

I claim:

The ornamental design for a toy tank, as shown.
